UNITED STATES PATENT OFFICE

ELIHU THOMSON, OF NEW BRITAIN, CONNECTICUT, ASSIGNOR TO THE THOMSON-HOUSTON ELECTRIC COMPANY.

DYNAMO-ELECTRIC MACHINE.

SPECIFICATION forming part of Letters Patent No. 281,416, dated July 17, 1883.

Application filed January 22, 1883. (No model.)

To all whom it may concern:

Be it known that I, ELIHU THOMSON, a citizen of the United States, and a resident of New Britain, in the county of Hartford and State 5 of Connecticut, have invented certain new and useful Improvements in Dynamo-Electric Generators, of which the following is a specification.

My invention relates, first, to the construction of an armature wound with two or more coils for dynamo-electric and magneto-electric generators in which the tension of the generated current is great; and it consists in improvements designed to make the use of such 15 currents practicable and easy and to increase the durability of the apparatus.

My improvement consists, first, in the use of a cylinder-ring or spherical armature-core or equivalent shell of iron made without any 20 conducting metallic projections, or at least without any such projections that approach near to the outer layers of insulated wire surrounding said core, and in winding said core, constructed as above, with insulated wire in 25 such a manner that high electric potentials in said wire shall be found only on the outside layers of said winding and farthest from said core. The object attained by the construction is the prevention of short-circuit faults through the 30 armature-core, from points of high potential of insulated wire to others of opposite or lower potential on a different part of said core. The armature-core itself is in certain cases, in addition insulated from all other parts of the machine. By combining the latter feature with 35 my mode of winding, I secure the safest possible construction. This latter combination is especially valuable where a number of machines are run in series, and where a possibility 40 of leak in the foundations upon which they rest exists.

Another part of my invention consists in using for those layers of the armature-coil that lie nearest the core of the armature a coarser 45 wire than is used for the outside layers, both wires being connected in series and acting together, thereby equalizing the resistance. By this arrangement the temperature of the underlying layers (which latter are not exposed to the free air, and therefore are liable 50 to become more heated than the outer layers)

is kept down. Two or more gradations of wire may be used, the finer being always nearer the outer surface. This construction tends to a uniform distribution of heat, and 55 renders the parts less liable to displacement and damage from unequal expansion produced by the higher temperature of the internal layers, which is liable to occur when the interior and exterior coils are of the same 60 size as is ordinarily the case.

Another part of my invention consists in the application to the outer wires of an armature of an interwoven string or tape, which binds said outer layers together and practically solidifies the winding and prevents disturbance of its position by accident or otherwise.

Figure 1 is a vertical section parallel to the shaft X of a cylindrical armature containing 70 one feature of my invention. Fig. 2 is an end view of the same. Fig. 3 illustrates my mode of winding, to be hereinafter described. Fig. 4 illustrates my mode of winding for equalization of temperature. Fig. 5 illustrates a 75 modification of the method shown in Fig. 4. Fig. 6 is a cross-section of a portion of an armature through the wires of the same when wound after the plan illustrated in Fig. 4. Figs. 7 and 8 show the method of binding the 80 outer layers of armature-wire. Fig. 9 shows another application of the same binding to the armature-wires. Fig. 10 illustrates the application of the various parts of my invention to an annular or ring armature. 85

In Fig. 1 is shown in section an ordinary cylindrical core or carrier, II, of iron, supported concentrically with the shaft X, but insulated from it. The end plates or flanges, FF, support the core I, which is of any usual 90 construction. Outside said core the armature coils of insulated copper are wound. One of said coils is indicated at CC, and several coils are in my invention supposed to be so wound, but in different angular positions as ordinarily. 95 All the coils are so wound as to bring their inner layers or wires nearest the core I of lowest electric potential, and this is effected by a union of all of said inner wire terminals or wires from the inner layers of the armature into a common joint, J. It will be seen that when this is done the difference of po-

tential between the lower and inner layers of one coil and that of any other will be slight, and that there will be little, if any, tendency to perforate the insulation and follow the iron core I I to any other point. This is not so in armatures used with several coils, in which an accumulation of potential takes place as the current passes successively through one coil after another, entering one coil near the iron core, leaving such coil from its outer layers, thence passing to the inner layers of the next coil, and leaving as before, and so on through several coils, so that wire at great differences of potential is near the core at different points. The same disadvantage exists where iron projections extend outward and approximate closely to the outer layers at high potential, and is a source of great danger to insulation in high-tension machines.

I do not use in my invention cores having iron projection approximating closely to the outer layers of my winding. I may, however, employ iron projections when the distance of such projections from the outer layers is made great, or when there is a free air-space separating such projections and layers.

Fig. 2 shows an end view of an armature like that of Fig. 1 wound with three coils, the free terminals of which are also the terminals from the outer layers of armature-wire, which armature has the greatest differences of electric potential at the points before described. These terminals *a b c* are carried to the commutator, or, when reversed currents are obtained, to insulated rings, as usual.

Fig. 3 is a symbolic figure showing that the three coils A B C have their inner terminals joined at J, while the outer terminals are free for conveying current from the coils. This disposition brings the highest tension at the greatest distance apart and far from any other conductors, insuring durability and freedom from leakages.

Fig. 4 shows the preferred disposition of the masses of copper composing the wire of a coil, A. The wire leaving J is larger in size than that at *a*, or the inner layers are of heavier wire than the outer ones. This prevents undue generation of heat in the inner layers, while the outer layers, having greater exposure for cooling, are, though of finer wire, kept cool by the circulation of air around them.

Fig. 5 shows an equivalent construction, in which the outer layers are of single wire of convenient size, while the inner layers are of double wire, the combined section of which is greater than the outer wire.

Fig. 6 shows the same subject-matter as Fig. 4; but the wires lying in layers outside the iron core are shown cut transversely and as of three sizes, the outer being the finest wire.

Figs. 7 and 9 illustrate my improved method

of giving stability to the outer layers of wire constituting parts of the armature, and preventing them from becoming displaced. Two or more tapes or cords, *t t*, are interwoven with the wires, alternately passing above and below the wire convolutions, as shown in Fig. 9, where the wires are separated for clearness. This is seen also in Fig. 8 at *t t*, where the tape binds the coils at the end of the armature to prevent its displacement during revolution around the axis X.

Fig. 10 shows a ring-armature wound as before—namely, the ends or terminals leaving a joint, J, are those from the inner layers of the armature-coils C C² C³ C⁴, while the outer layers have their terminals free to be carried to a commutator of any suitable construction. If projections extend from the core of the armature, and these projections are of iron, the winding is accomplished, so that as successive layers are wound on the armature-coil the distance between the projections *p p* and said outer layers is increased, as shown at *s s*.

What I claim as my invention is—

1. In an armature of cylindrical, annular, or spherical form, made without conducting projections, or without projections that approach near to the outer layers of armature-wire, a system of two or more coils wound, as described, so as to bring the highest electric potential upon the outer layers of said windings only, as and for the purpose set forth.

2. In an armature of cylindrical, annular, or spherical form, made without conducting projections, or without projections that approach near to the outer layers of armature-wire, a system of two or more coils the terminals from the inner layers of which are joined, while the terminals from the outer layers are carried to the commutator, as described.

3. In a dynamo-electric or magneto-electric machine, an armature-coil the inner layers of which are of coarser wire or conductor than the outer layers, for the purpose set forth.

4. The combination, with the outer layers of wire in the armature, of one or more tapes or cords interwoven with said layers, substantially as set forth.

5. As a means for preventing displacement of the coils of wire upon an armature, an interwoven tape or tapes uniting and solidifying contiguous convolutions of wire, substantially as set forth.

Signed at New Britain, in the county of Hartford and State of Connecticut, this 17th day of January, A. D. 1883.

ELIHU THOMSON.
